WIRE BASKET CONSTRUCTION

Clarence S. Glenny, Rockford, Ill., assignor to The Washburn Company, Worcester, Mass., a corporation of Massachusetts

Application June 29, 1956, Serial No. 594,901

10 Claims. (Cl. 220—19)

This invention relates to a new and improved wire basket construction.

The principal object of my invention is to provide a basket, the corners of which are all neatly closed and are at the same time reinforced, by virtue of the novel method of welding right-angle bent edge portions on the opposite ends of the basket in overlapped relationship to the adjacent ends of the other two sides.

Another feature of the invention is the elimination of raw ends on the horizontal wires of the end walls by providing upwardly bent end portions on the lowermost horizontal wires on the end walls and having the ends of all of the other horizontal wires on the end walls welded to these upwardly bent end portions. The upwardly bent end portions have their upper ends looped around the top frame on the far side of loops on the upper ends of the endmost vertical wires of the adjacent side walls to provide an additional overlapping tie at each corner for maximum strength.

The invention is illustrated in the accompanying drawing, in which—

Fig. 1 is a view of the cross-shaped wire blank for the body of the basket;

Fig. 2 is a perspective view of one corner of the body portion of the basket as it appears after two forming operations on the blank in which—

(1) The opposite side portions of the end wall portions are bent upwardly, and

(2) The side wall portions are bent upwardly relative to the bottom portion, and the end wall portions are bent upwardly, disposing the bent side portions of the end walls in overlapping relationship to the adjacent ends of the side walls;

Fig. 3 is a perspective view of one corner of the completed basket, the overlapping portions having been pressed together and welded and the upper ends of all of the upwardly extending wires having been looped around and welded to the wire top frame, and

Fig. 4 is a horizontal sectional detail on the line 4—4 of Fig. 3.

The same reference numerals are applied to corresponding parts in these four views.

Referring to the drawing, the flat welded cross-shaped wire blank B shown in Fig. 1 has spaced parallel wires 5 welded at the intersections to other spaced parallel wires 6 disposed at right angles thereto to define a rectangular bottom portion 7 for the basket and opposed side wall portions 8 and 9 of rectangular form. The wires 6 in the bottom portion 7 extend from both ends of the bottom portion 7 and have spaced parallel wires 10 welded thereto at the intersections in right angle relationship to define opposed end wall portions 11 and 13 for the basket. The wires 10 form the horizontal wires in the end walls of the basket and the lowermost one of these has end portions which are bent, as at 14, to provide upwardly extending portions 15 welded thereto, as indicated at 16, to the extremities of the wires 10 so as not to leave any raw ends projecting. In one forming operation, the side portions 18 of the end wall portions 11 and 12 are bent upwardly, as at 19. Then, in another forming operation, the side wall portions 8 and 9 are bent upwardly with respect to the opposite sides of the bottom 7, as indicated

2

at 17 in Figs. 2 and 3, and the end wall portions 11 and 12 are bent upwardly, as indicated at 20 in Figs. 2 and 3, disposing the inwardly bent side portions 18 of the end wall portions 11 and 12 in overlapping relation to the outer side of the adjacent ends of the side walls 8 and 9, as seen in Fig. 2. After this, the overlapping portions are pressed together and welded, as shown in Figs. 3 and 4, the upwardly bent end portions 15 of the lowermost horizontal wires 12 being welded to the outer side of the horizontal wires 6 of the side walls 8 and 9, as at 21, while the vertical wires 5 in the side walls 8 and 9 are welded, as at 22, to the inner side of the bent end portions of the horizontal wires 10 in the end walls 11 and 12. This tieup between the bent portions 18 of the end walls 11 and 12 with the overlapped end portions of the side walls 8 and 9 makes for neatly closed corners on the basket, which is particularly desirable in the case of locker baskets and also makes for considerable strength and rigidity of the basket generally, and, of course, particularly in the corner portions.

The upper ends of the wires 5 and 6 in the four walls of the basket are looped around the rectangular wire top frame 23 of the basket, as indicated at 24 and 25, respectively, in Fig. 3, and the upper ends of the upwardly bent end portions 15 of the lowermost horizontal wires 10 are also looped around and welded to the top frame 23, as indicated at 26, and the fact that the loops 26 are on the far side of the endmost loops 24 of the adjacent side walls 8 and 9 relative to the end walls 11 and 12 makes for added strength by this additional tie-in of the end walls with the side walls.

It is believed the foregoing description conveys a good understanding of the objects and advantages of my invention. The appended claims have been drawn to cover all legitimate modifications and adaptations.

1 claim:

1. In a wire basket construction, a body constructed of a network of wire providing a rectangular bottom, opposed side walls extending upwardly from two sides of the bottom, and opposed end walls extending upwardly from the other two sides of the bottom, the side and end walls including vertically spaced horizontal wires welded to spaced parallel vertical wires, said end walls having lateral extension portions and the lowermost horizontal wires of said end walls having the opposite end portions thereof bent upwardly and welded to the extremities of the other horizontal wires of said end walls at the outer ends of said lateral extensions, and said lateral extensions being bent substantially at right angles with respect to said end walls and disposed in overlapping abutting relation to the adjacent end portions of the side walls and welded thereto.

2. In a wire basket construction, a body constructed of a network of wire providing a rectangular bottom, opposed side walls extending upwardly from two sides of the bottom, and opposed end walls extending upwardly from the other two sides of the bottom, the side and end walls including vertically spaced horizontal wires welded to spaced parallel vertical wires, said end walls having lateral extension portions and the lowermost horizontal wires of said end walls having the opposite end portions thereof bent upwardly and welded to the extremities of the other horizontal wires of said end walls at the outer ends of said lateral extensions, and said lateral extensions being bent substantially at right angles with respect to said end walls and disposed in overlapping abutting relation to the adjacent end portions of the side walls and welded thereto, and a rectangular wire top frame to which the upper ends of the vertical wires of said side and end walls are secured.

3. In a wire basket construction, a body constructed of a network of wire providing a rectangular bottom,

opposed side walls extending upwardly from two sides of the bottom, and opposed end walls extending upwardly from the other two sides of the bottom, the side and end walls including vertically spaced horizontal wires welded to spaced parallel vertical wires, said end walls having lateral extension portions and the lowermost horizontal wires of said end walls having the opposite end portions thereof bent upwardly and welded to the extremities of the other horizontal wires of said end walls at the outer ends of said lateral extensions, and said lateral extensions being bent substantially at right angles with respect to said end walls and disposed in overlapping abutting relation to the adjacent end portions of the side walls and welded thereto, and a rectangular wire top frame onto which the upper ends of the vertical wires of the side and end walls are looped and welded, the upper end portions of the upwardly bent ends of the lowermost horizontal wires of said end walls being also looped around said top frame and welded thereto.

4. In a wire basket construction, a body constructed of a network of wire providing a rectangular bottom, opposed side walls extending upwardly from two sides of the bottom, and opposed end walls extending upwardly from the other two sides of the bottom, the side and end walls including vertically spaced horizontal wires welded to spaced parallel vertical wires, said end walls having lateral extension portions and the lowermost horizontal wires of said end walls having the opposite end portions thereof bent upwardly and welded to the extremities of the other horizontal wires of said end walls at the outer ends of said lateral extensions, and said lateral extensions being bent substantially at right angles with respect to said end walls and disposed in overlapping abutting relation to the adjacent end portions of the side walls and welded thereto, and a rectangular wire top frame onto which the upper ends of the vertical wires of the side and end walls are looped and welded, the upper end portions of the upwardly bent ends of the lowermost horizontal wires of said end walls being also looped around said top frame and welded thereto, the last mentioned loops being on the far side of loops of the side wall wires with respect to the end walls.

5. A basket corner construction comprising adjoining walls, one of which includes vertically spaced parallel horizontal wires fastened at their intersection points to spaced parallel vertical wires, said wall having a lateral extension portion, and one of the lower horizontal wires of said wall having the end portion thereof bent upwardly in transverse relation to the end portions of the other horizontal wires above it and fastened thereto to define the lateral edge of said lateral extension, said lateral extension being bent into overlapping abutting relationship to the other wall and fastened thereto.

6. A basket corner construction comprising adjoining walls, both including vertical wires, a wire top frame having a corner portion to the adjoining portions of which the upper ends of the vertical wires of said adjoining walls are secured, one of said walls including vertically spaced horizontal wires fastened at their intersection points to the vertical wires thereof, said wall having a lateral extension portion, and one of the lower horizontal wires of said wall having the end portion thereof bent upwardly in transverse relation to the end portions of the other horizontal wires above it and fastened thereto to define the lateral edge of said lateral extension, said lateral extension being bent into overlapping abutting relation to the adjoining wall and the upper end of the upwardly bent wire being secured to said wire top frame.

7. A basket corner construction comprising adjoining walls, both including vertical wires, a wire top frame having a corner portion to the adjoining portions of which the upper ends of the vertical wires of said adjoining walls are secured, one of said walls including vertically spaced horizontal wires fastened at their intersection points to the vertical wires thereof, said wall

having a lateral extension portion, and one of the lower horizontal wires of said wall having the end portion thereof bent upwardly in transverse relation to the end portions of the other horizontal wires above it and fastened thereto to define the lateral edge of said lateral extension, said lateral extension being bent into overlapping abutting relation to the adjoining wall and fastened thereto; and the upper end of the upwardly bent wire being secured to said wire top frame on the far side of at least one of the points of connection to the top frame of a vertical wire in said adjoining wall.

8. A basket corner construction comprising adjoining walls, both including vertical wires, a wire top frame having a corner portion to the adjoining portions of which the upper ends of the vertical wires of said adjoining walls are secured by loops, one of said walls including vertically spaced horizontal wires welded thereto at their intersection points to the vertical wires thereof, said wall having a lateral extension portion, and one of the lower horizontal wires of said wall having the end portion thereof bent upwardly in transverse relation to the end portions of the other horizontal wires above it and welded thereto to define the lateral edge of said lateral extension, said lateral extension being bent into overlapping abutting relation to the adjoining wall and welded thereto and the upper end of the upwardly bent wire being secured to said wire top frame by a loop on the far side of the loop of at least one of the vertical wires of said adjoining wall.

9. In a wire basket construction, a body constructed of a network of wire providing a rectangular bottom, opposed side walls extending upwardly from two sides of the bottom, and opposed end walls extending upwardly from the other two sides of the bottom, the side and end walls including vertically spaced horizontal wires secured to spaced parallel vertical wires, one of said end walls having lateral extension portions and one of the lower horizontal wires of said end wall having the opposite end portions thereof bent upwardly and secured to the extremities of the other horizontal wires above it in said end wall at the outer ends of said lateral extensions, and said lateral extensions being bent substantially at right angles with respect to said end wall and disposed in overlapping abutting relation to the adjacent end portions of the side walls and secured thereto.

10. In a wire basket construction, a body constructed of a network of wire providing a rectangular bottom, opposed side walls extending upwardly from two sides of the bottom, and opposed end walls extending upwardly from the other two sides of the bottom, the side and end walls including vertically spaced horizontal wires secured to spaced parallel vertical wires, one of said end walls having lateral extension portions and one of the lower horizontal wires of said end wall having the opposite end portions thereof bent upwardly and secured to the extremities of the other horizontal wires above it in said end wall at the outer ends of said lateral extensions, and said lateral extensions being bent substantially at right angles with respect to said end wall and disposed in overlapping abutting relation to the adjacent end portions of the side walls and secured thereto, and a rectangular wire top frame to which the upper ends of the vertical wires of said side and end walls and the upper ends of the upwardly bent end portions of said lower horizontal wire are secured.
